UNITED STATES PATENT OFFICE.

WILLIAM L. WEST AND JAMES F. WEST, OF BELMONT, NORTH CAROLINA.

TOY AEROPLANE.

Application filed May 21, 1928. Serial No. 279,430.

The present invention relates to toy aeroplanes and has for its principal object to provide a captive plane pivotally supported at one end of a weighted arm and mounting 5 the arm for rotative movement intermediate its ends whereby to provide for the movement of the aeroplane in a circle upon the operation thereof.

A further object of the invention is to 10 provide an electric motor within the body of the aeroplane for driving the propeller thereof and operatively connecting the motor to circuit wires extending through the arm and support therefor, whereby to provide 15 for the operation of an aeroplane.

An additional object is to provide a device of this character of a simple and practical construction which is neat and attractive in appearance, strong and durable, and 20 relatively inexpensive to manufacture and maintain in operation, and otherwise well adapted to the purposes for which the same is intended.

Other objects and advantages reside in 25 the special construction and combination of the various elements comprising the invention, reference being had to the accompanying drawings, forming a part hereof, wherein:

30 Figure 1 is a top plan view.

Figure 2 is a view in side elevation.

Figure 3 is a vertical sectional view 35 through the supporting standard for the weighted arm.

Figure 4 is a side elevational view of the aeroplane with parts broken away and showing the manner of mounting the electric motor therein, and

Figure 5 is a fragmentary longitudinal 40 sectional view through the contact member carried by the weighted arm.

Referring now to the drawing in detail, wherein for the purpose of illustration we have shown a preferred embodiment of our 45 invention, the numeral 5 designates a track upon which the aeroplane 6 is adapted to travel while arising into a position for flight, the said track being of an annular formation and provided with a base 7 concentrically disposed with respect thereto, and connected with the track by means of radially extending braces 8. Upon the base 7 is arranged a standard 9 of tubular formation having each end opened and provided 50 at its upper end with a cap 10 having a reduced lower portion 11 inserted within

the upper end of the standard, and an annular shoulder 12 formed on said cap adapted to seat upon the upper edge of said standard. The cap 10 is fitted upon the 60 standard with sufficient freedom to permit the free rotation of the cap thereon.

The upper portion of the cap is bifurcated as shown at 13 and between the sections thereof is arranged a pin 14 providing 65 a pivotal mounting for an arm 15, with its ends extending outwardly at opposite sides of the standard. One end of the arm 15 is pivotally supported on a pin 16 extending between the bifurcated end 17 of an attaching member 18, to which an aeroplane of conventional construction, indicated at 19, is suspended. Within the body or fuselage of the aeroplane is mounted an electric motor 20 having its shaft extending forwardly through the front end of the body of the aeroplane and having a propeller 21 mounted thereon. The motor 20 is connected by circuit wires 22 leading through the arm 15 to a point adjacent its pivotal mounting, the wire 22 then extending outwardly through the arms for connection with a brush 23. The wire 22 and brush 23 are suitably insulated from the arm, as is shown at 24. Upon the standard adjacent 70 the upper end thereof is mounted a collar 25, having a section of insulation material 26, interposed between the collar and the standard, said collar having a circuit wire 27 attached thereto and extending through 75 the wall of the standard and downwardly therethrough and outwardly at the lower end of the standard for connection with a suitable source of power.

The wire 27 thus constitutes a feed wire 80 for the motor, being connected therewith through the collar 25 and brush 23, which communicates with the motor through the wire 22, for supplying current thereto, the motor being grounded, to the supporting 85 member 18, arm 15 and standard 9. The end of the arm 15, opposite from the aeroplane is threaded, as shown at 28, and upon which threaded end is threadably mounted a weight 29, operating as a counter-balance 90 for the aeroplane.

It will be apparent from the foregoing 95 that the supplying of current through the wire 27, the motor of the aeroplane will be operated, so as to drive the propeller, and through its rotation, the aeroplane will be 100 moved, in a manner well known in the art.

Through the pivotal mounting of the arm 15, the aeroplane will be enabled to travel in a circuit direction around the track 5, the current being continuously supplied for 5 operating the motor through the brush and collar 23 and 25 respectively. By properly adjusting the weight 23 on the arm, the aeroplane will be permitted to rise above the surface of the track as the momentum 10 thereof increases, and thus the toy aeroplane will simulate an actual aeroplane in flight.

It is obvious that the invention is susceptible of various changes and modifications, without departing from the spirit or 15 scope of the invention or sacrificing any of its advantages, and we accordingly claim all such forms of the device to which we are entitled.

Having thus described our invention, what 20 we claim as new is:

A toy of the class described comprising a base, an annular track surrounding said base and spaced therefrom, means for connecting said track to said base, a supporting stand-

ard rising from the base, a cap rotatably 25 mounted on the upper end of said standard, and an arm pivotally supported intermediate its ends on said cap, a toy aeroplane pivotally attached to one end of the arm for rest upon said track, counter-balancing means 30 for the aeroplane adjustably arranged at the opposite end of the arm, and operating means for the aeroplane comprising an electric motor mounted therein, and operatively connected with the propeller of the aeroplane, a brush carried by the arm adjacent its pivotal connection, a collar mounted on the standard adjacent its upper end in contacting relation with said brush, said brush and said collar being insulated respectively 35 from the arm and the standard, a circuit wire connecting said collar with a source of supply, and a circuit wire connecting said brush with said motor.

In testimony whereof we affix our 40 signatures.

JAMES F. WEST.

WILLIAM L. WEST.
